of Delaware

Application October 26, 1946, Serial No. 705,951

11 Claims. (Cl. 313—252)

1

The present invention relates to electron discharge devices, and more particularly to electron discharge devices useful at ultra high frequencies, and to a method of manufacture and assembly of such devices.

Electron discharge devices designed for ultra high frequency operation are more limited as to structure than devices for use at lower frequencies. For example, the electrode elements in an ultra high frequency electron discharge device must observe closer tolerances in spacings relative to each other and must maintain such critical spacings during operation of the device. In addition the electrode leads for such devices must be characterized by critical dimensions and spacings to avoid undesired capacity effects therebetween. Although these factors require recognition, to a lesser or greater extent, in all types of electron discharge devices they become more critical as the frequency at which the devices operate is increased.

These structural limitations present obvious problems in the manufacture of such devices, particularly by mass production methods. One of the problems concerns the selection of the most desirable type of electrode elements. Thus, in some types of electron discharge devices useful at ultra high frequencies, planar type electrode elements have been utilized; for example, in triodes a flat grid is interposed between a flat surfaced cathode and a flat surfaced anode, both closely spaced from the grid. In other types of such devices, concentric electrode elements have been proposed. In certain respects concentric electrode elements are more advantageous than planar electrodes. For example, less heater power is required for devices using concentric electrodes than for those having planar electrodes, since in the former heat in all radial directions is utilized for producing electron emission whereas in the latter the heat in one plane only is made use of for this purpose. Furthermore, it is possible to more effectively maintain the desired alignment and spacing of concentric electrode elements during operation, once these have been fixed in manufacture, for the reason that heat produced during operation affects concentric elements in a radial sense which does not substantially disturb the spacings therebetween.

Another problem involves the structure of the electrode leads. To reduce undesired capacity effects between leads to the input and output electrodes of an ultra high frequency electron discharge device, they should be as short as pos-

2

sible and spaced from each other as far as possible. This has resulted in the practice of taking the leads from spaced apart locations on the device envelope. One expedient has been to make these leads integral with the envelope, one lead being contributed by an end portion of the envelope and the other lead being formed by a disc sealed through the envelope wall. However, this arrangement is accompanied by the danger that unless the disc is sealed to the envelope prior to the fixing of the electrodes therein, the greater quantity of heat required for the larger disc envelope seal will harmfully affect the mounting of the electrodes, and any other seals previously made in assembling the device. It is, therefore, desirable in the manufacture of the device that the steps followed in assembly be characterized by a descending order of heat quantity required therein to safeguard the seals produced by such heat.

Another matter that requires consideration in the manufacture of an electron discharge device is the preservation of the electrodes from oxidation. In methods of assembly which require placement of the electrodes in the envelope of the device prior to effecting the various seals for completing the envelope, there is danger that the heat required for such seals might harmfully oxidize the previously sprayed electrodes. It is obviously desirable therefore, that the manufacturing procedure involve completion of the seal for forming the envelope prior to insertion of the electrodes therein.

It is an object of my invention to provide an improved electron discharge device useful at ultra high frequencies.

Another object of my invention is to provide a structure for and a method of assembling an electron discharge device which will facilitate assembly and insure good seals.

A further object is to provide a method of fabricating electron discharge devices useful at ultra high frequencies in which spacing of the electrode elements is determined in a positive manner by elements previously assembled and sealed.

An additional object is to provide a method of making an electron discharge device useful at ultra high frequencies, having hollow electrodes which follow an order in manufacture assuring good seals and a minimum oxidation of the electrodes thereof.

Another object is to provide a method of making an electron discharge device from previously prepared parts formed to permit the use of cen-

tering means for automatically centering and spacing the parts during assembly and to permit an order to be followed in the use of heat to preserve previously fixed elements of the device and to reduce oxidation of the electrodes of the device.

For a better understanding of my invention reference will now be made to the accompanying drawings which show embodiments of my invention for purposes of illustration only and not by way of limitation, in which:

Figure 1 shows a triode, in section, made according to my novel method wherein the anode is supported in the central aperture of the disc lead-in conductor, the electrodes and envelope being cylindrical;

Figure 2 is an exploded view, partly in section, of the relationship of the parts employed in my novel method of fabricating the ultra high frequency triode shown in Figure 1;

Figure 3 shows in section, a step in my novel method wherein the parts forming the walls of the envelope are assembled on a centering pin prior to the sealing together of the parts; and

Figure 4 is a view in section of the jig used for centering and mounting the grid on its support;

Figure 5 shows in section a modification wherein the grid is supported on the disc lead-in conductor; and

Figure 6 is a view in section of a further modification wherein the chambers or passageways in the end portions of the envelope are formed by tapered walls and the centering pin is provided within certain longitudinal sections of tapered elevation.

Referring now to the drawing in more detail, there is shown in Figure 1 an ultra high frequency triode made in accordance with the method of my invention which includes an envelope and electrodes mounted therein. The envelope includes a tubular metallic flanged end section 1, a tubular glass section 2, a second tubular glass section 3 and a tubular metallic flanged end section 4. Each of these envelope sections defines an open-ended chamber or passageway. The electrodes, which in this embodiment are cylindrical in shape, comprise an anode 5, a cathode 6, and a grid 7, which are concentrically disposed and have equal lengths. Supports are provided for each of the electrodes.

Cathode support 8 has a hollow interior affording accommodations for cathode heater leads 9 and getter 10. This support 8 is mounted with a portion thereof in snug engagement with the interior wall of tubular end section 1 and fixed in position thereon by brazing 14. The open end of cathode support 8 is sealed by a vitreous closure member 11.

The grid support 12 has a channelled interior affording communication between the interior of the envelope and exhaust tube 13, shown pinched off after exhaust. A portion of support 12 forms a snug fit with the interior wall of the tubular end section 4 and is fixed in position thereto by being brazed thereto at 15. Both the cathode support 8 and grid support 12 abut end surfaces of the tubular end portions 1 and 4 of the envelope to fix their longitudinal spacings.

The anode support comprises a disc 16 having a central aperture in which anode 5 is mounted. This disc is sealed across the tubular glass sections 2 and 3 by glass-to-metal seals 17, 18, 19 and 20.

A feature of the method of my invention resides in first assembling and sealing together the larger side wall sections 1, 2, 3 and 4 of the en-

velope and disc 16 with opposite ends of the envelope open for subsequent insertion and mounting of the electrodes therein. This completes the larger seals 17, 18, 19 and 20 before the other seals, closing the ends of the envelope and requiring a lesser quantity of heat, are made. This feature permits the use of disc 16 as an electrode support and as a lead-in conductor without danger that the sealing thereof to the envelope might impair other seals of the device. This feature also provides for insertion of the electrodes within the envelope after the larger seals have been completed, thus preventing oxidation of the electrodes by the heat required for such larger seals.

Another feature of the invention is the provision of previously prepared parts for forming the envelope and the electrode assembly, which are correlated in shape and dimensions to a centering and spacing means employed in the manufacture of the device. This feature of the invention requires that the parts for forming the envelope side wall be first assembled and sealed, leaving end portions open for insertion of electrodes and their supports into the envelope in predetermined locations for forming snug fits between the electrode supports and interior wall portions of the envelope.

The open ended chambers or passageways 34, 36 in flared end sections 4 and 1, shown in Figure 2, have dimensions for receiving in snug fits portion 12a of grid support 12 and portion 8a of cathode support 8, respectively. The end chambers 34, 36 are accurately aligned axially by a jig or centering pin to be described. The grid 7 and cathode 6 are also accurately aligned axially with respect to their supports 12 and 8, which alignment may be accomplished in the manner shown in Figure 4. As will be more fully described, the anode 5 is also accurately aligned axially with respect to chambers 34, 36 by the centering pin referred to. The supports 12a and 8a for the grid and cathode are of a length to dispose the grid 7 and cathode 6 in concentric relation with respect to each other and with respect to anode 5 when the supports referred to are extended into the end chambers 34, 36.

In a modification to be described and as shown in Figure 5 the central aperture in disc 16 is provided with walls that define a chamber that is aligned with respect to the end chambers formed in end members 1 and 4. In this modification therefore three axially aligned chambers are provided for receiving electrode supports for disposing the electrodes in coaxial and concentric relation.

It will be noted that my invention provides for an electrode arrangement wherein the electrodes are of different diameter to permit a first electrode to telescope into a second electrode, and to permit the first and second electrodes to telescope into a third electrode. All the electrodes are therefore coextensive axially of the device and in registering relation around a common axis. The requirement for a common axis for the electrodes and coextensive disposition of the electrodes results in an electrode arrangement wherein the electrodes are spaced from each other radially of said axis and in all directions normal to said axis.

Therefore, the feature of my invention which requires that the side walls of the envelope of the device be first assembled and sealed, is advantageous from the several standpoints of preserving the seals of the device, avoiding the danger of oxidation of the electrodes, and properly align-

ing and spacing the electrodes within the envelope. Figure 2 shows an exploded view of the relationship of the previously prepared parts which when assembled and sealed together form the structure of my novel electron discharge device. In this modification of my invention the previously prepared parts, with the exception of the cathode heater, are cylindrical in form and include cathode 6, mounted on the support 8 and energized by cathode heater 21 having leads 9 sealed through insulating closure member 11, which seals the open end of cathode support 8. The envelope side wall portions include metallic end portions 1 and 4 and cylindrical glass members 2 and 3. The anode structure includes disc 16 supporting anode 5. The grid structure includes grid support 12 and grid 7. Exhaust tube 13 is in position to be sealed over the opening in grid support 12 for communicating with the interior of the envelope. The metallic parts 8, 1, 4, 12 and 13 are sealed together by brazing rings 14, 15 and 22.

The dimensions and shapes of each of these previously prepared parts are predetermined in relation to dimensions and shapes of predetermined portions of a centering pin 23 shown in Figure 3. This figure shows the parts for forming the envelope assembled on centering pin 23 prior to sealing. The cylindrical interior space of member 1 forms a snug fit with the offset portion 23a of pin 23 and rests on a shoulder 24 thereof. The cylindrical anode 5 forms a tight fit around another portion 23b of pin 23 and is limited in downward movement by shoulder 25 on this pin. Envelope member 24 forms a snug fit around a still further offset portion 23c of pin 23 and is limited in downward movement by shoulder 26 on the pin. Since the offset portions referred to of pin 23 are accurately centered, a snug engagement therewith of envelope members 1 and 4 and anode 5 results in an alignment of these members and anode 5. Since anode 5 is mounted in the center of disc 16, the alignment of anode 5 with members 1 and 4, also results in the alignment of disc 16 with these members, assuming the anode has been mounted on disc 16 prior to this assembly step.

Envelope end members 1 and 4 are each provided with a flange having annular ribs or guides 27 and 28 for engagement with end portions of cylindrical glass members 2 and 3. Such engagement of cylindrical glass members 2 and 3 with the annular ribs or guides 27-28 results in an alignment of these glass cylinders with envelope end portions 1 and 4. The alignment of these cylindrical glass members 2 and 3 with envelope portions 1 and 4 completes the alignment of all the parts entering into the structure of the device envelope.

The next step involves the sealing together of the envelope parts referred to while maintaining their aligned relationship. The desired longitudinal spacing of the parts referred to is accomplished during the seal operation to be described. The sealing operation involves the application of heat to form glass-to-metal seals between cylindrical glass member 2, the envelope end member 1 and the disc 16. When the seal is effected between these members, anode 5 rests on shoulder 25 of pin 23. Each of the offset portions 23a, 23b and 23c is characterized by a predetermined length. Therefore when anode 5 rests on shoulder 25 of pin 23 there is a predetermined longitudinal spacing between the lower

edge of anode 5 and the lower end of envelope end portion 1. The next step is the sealing of the glass member 3 to disc 16 and the envelope end portion 4. When these seals are accomplished the envelope end portion 4 rests on shoulder 26 of pin 23. The longitudinal spacing between the upper edge of anode 5 and the upper end of envelope end portion 4 is, therefore, of a predetermined magnitude.

10 The steps thus far described have resulted in an accurate alignment of the parts forming the envelope of my device and a proper longitudinal spacing therebetween. The next step involves the mounting of electrodes and electrode supports within the envelope wherein the aligned and appropriately spaced parts referred to automatically align and properly space the electrodes within the device.

15 In the modification of my invention presently described, the cathode and grid electrodes constitute parts of a previously prepared structure which include these electrode as well as supports therefor. These electrodes and their supports observe predetermined dimensional values so that the electrode supports have a portion thereof which forms a snug fit with internal chambers or passageways defined by envelope end members 1 and 4. The cathode and grid electrodes are each suitably centered on their supports so that when these supports engage the interior walls of the envelope end members 1 and 4, these electrodes are accurately aligned. The cathode and grid supports are also provided with portions thereof which limit their longitudinal movement within said end portions 1 and 4. This limitation of longitudinal movement of the cathode and grid supports results in an accurate longitudinal spacing of the cathode and grid with respect to each other as well as with respect to the anode 5.

20 Figure 4 shows a jig which I may employ for centering the grid 7 on its support 12. This jig includes an outer member 29 for holding the grid support 12 and an inner member 30 fitting snugly into the outer member 29 for holding the grid 7 in appropriately aligned and spaced relationship with respect to support 12. Members 29 and 30 may be made of metals having different coefficients of expansion, so that the inner member expands more than the outer member when similarly heated to accomplish a tight fit between these members to more accurately align them. Members 29 and 30 are given longitudinal movement relative to each other until the upper end of grid 7 abuts the lower end of grid support 12 as viewed in Figure 4. Sufficient clearance around grid 7 is provided for brazing ring 32, which is heated through aperture 31 in member 29 to fix grid 7 to its support. Jig members 29 and 30 are so constructed that they hold the grid 7 and the grid support 12 in accurate alignment and longitudinal spacing during the brazing step. A jig employing similar principles may be used to center cathode 6 on its support 8.

25 After the cathode and grid electrodes are thus accurately mounted on their supports, they are inserted into the envelope. Grid 7 and grid support 12 are inserted in the envelope and section 4 with shoulder 33 of grid support 12 abutting against the upper end of end portion 4 and sealed thereto by brazing ring 15. During this brazing step, a cooling clamp may be employed to absorb the heat required for the brazing. The portion 12-a of the grid support fits snugly with 30 in the cylindrical space 34 of envelope end por-

tion 4. This results in an accurate alignment and spacing of grid 7 with respect to anode 5.

Cathode 6 and cathode support 8 are next inserted in envelope end portion 1 with the shoulder 35 of the cathode support abutting against the lower end of this portion. The portion 8a of the cathode support fits snugly within the cylindrical space 36 in the envelope end portion 1. This results in an accurate alignment and spacing of cathode 6 with respect to grid 7 and anode 5.

As has been stated before herein, the longitudinal dimensions of the cathode and grid and their supports are predetermined, whereby the cathode and grid each may have a length equal to that of the anode. The cathode and grid supports are each provided with a length from their shoulders 33 and 35 to their electrode supporting ends which accurately positions the cathode and grid within the cylindrical space defined by anode 5. The electrodes, therefore, are accurately aligned and may be characterized by a displacement that extends only in a radial or lateral sense.

Cathode heater 21 is next inserted into the cathode 6 and the open end of the cathode support is sealed by sealing member 11.

The grid 7 and grid support 12 are provided with a channel communicating with the interior of the device envelope. Exhaust tube 13 is next brazed to the upper end of this channel as viewed in Figures 1 and 2 by brazing ring 22 and the envelope is evacuated. The exhaust tube is then closed as by pinching and the device is complete.

It will be seen, therefore, that according to the novel method of my invention electrodes are mounted in critically aligned and spaced relationships within an envelope, the resultant structure being characterized by many advantages. Moreover this method inherently provides a procedure which permits the desired type of leads for ultra high frequency use to be employed while assuring good seals, freedom from oxidation of the electrodes by the heat required for such seals, and unimpaired fixed mounting of the electrodes within the envelope of the device.

Figure 5 shows a modification wherein the grid 7 is suitably mounted in a central aperture of disc 16. Anode 5 is supported at one end of the envelope on a support 38 on which it is suitably centered, as by a jig of the type previously referred to. Anode support 38 is brazed to the envelope end member 1 at 39. The cathode 6 is mounted on support 40, which is brazed to envelope end member 4. In this modification the anode 5 occupies the larger cylindrical space 36 in end member 1 while the cathode support occupies the smaller cylindrical space in end member 4. This modification requires no change in the structure of envelope end members 1 and 4, or of glass cylindrical members 2 and 3. It does, however, require a modification of the structure of cathode support 40 and anode support 38. The exhaust tube is shown brazed to the end of anode support 38, the support and anode having interior channels communicating with the interior of the envelope.

Figure 6 shows a further modification wherein a centering pin 41 has tapered portions 42 and 43 which engage correspondingly tapered interior wall portions of envelope end members 44 and 45. Pin 41 is provided with a cylindrical portion 46 which receives anode 5 in a snug fit. In this modification anode 5 and envelope end portion 44 are accurately centered by engaging cylindri-

cal portion 46 and tapered portion 43, respectively, of the pin. Envelope end portion 45 becomes centered only during the sealing operation when this member is brought into snug engagement with tapered portion 42 of pin 41. The tapered portions of pin 41 accomplish both a centering and accurate longitudinal spacing of envelope end portions 44 and 45 and anode 5. Cylindrical glass members 2 and 3 are centered in a manner previously described. The other electrodes are also suitably aligned and longitudinally spaced with respect to the anode 5 by engagement of their supports with the interior tapered walls of envelope end portions 44 and 45. The remaining steps for the completion of the device are similar to those referred to in connection with previously described modification of Figures 1 and 2.

While the invention has been described by reference to several embodiments thereof it is to be clearly understood it is not limited thereto. While these embodiments involve the use of cylindrical and tapered parts, it is obvious that parts of other configuration may be used without departing from the invention; and although the use of the invention in a triode has been described it can with equal advantage be employed in a diode or in a device having more than three electrodes. It is, therefore, desired to include these and other modifications which may suggest themselves to persons skilled in the art within the scope of the appended claims.

I claim:

1. An ultra high frequency electron discharge device having an envelope and electrodes mounted therein, end portions of said envelope defining end chambers therein of predetermined dimensions, said portions being in alignment with each other, and supports for said electrodes extending into said chambers, said supports having predetermined dimensions for snug engagement with the side walls of said end chambers and for supporting said electrodes in predetermined spaced relation within said envelope, and including portions having larger transverse areas than said electrodes, and other portions transversely coextensive with respect to said electrodes.

2. An ultra high frequency electron discharge device having an envelope and at least two electrodes mounted therein, wall portions of said envelope at opposite ends thereof defining chambers therein of predetermined dimensions, said wall portions being in alignment in predetermined spaced relation, supports for said electrodes extending into said chambers and having predetermined dimensions for snug engagement with the walls of said chambers and for supporting said electrodes in predetermined registered spaced relation, said electrodes being automatically aligned and accurately positioned in said envelope when said supports are received within said chambers.

3. An ultra high frequency electron discharge device having an envelope and at least three tubular electrodes mounted therein, said envelope having metallic end portions and a tubular insulating middle portion, said end portions having smaller transverse sections than said middle portion, a metallic disc sealed through said middle portion, one of said electrodes being supported by said disc within said envelope, said metallic end portions having walls defining spaces of predetermined dimensions, supports for two other of said electrodes extending into said end portions, said supports having predetermined dimen-

sions for forming a snug fit with said walls, and for supporting said two other of said electrodes in telescoped and concentric relation with respect to each other and with respect to said one of said electrodes.

4. An ultra high frequency electron discharge device having an envelope and two electrodes mounted therein, said envelope having a metallic end portion and a glass portion, said end portion having walls defining a chamber of predetermined dimensions, a metallic disc sealed to said glass portion, a hollow electrode supported on said disc within said envelope, and a support for the other of said electrodes extending into said chamber and having dimensions for forming a snug fit with said walls of said chamber, and for supporting said other of said electrodes in alignment with said first-mentioned electrode and in predetermined radially displaced relation thereto.

5. An ultra high frequency electron discharge device having an envelope and electrodes mounted therein, said envelope defining two aligned spaces at opposite ends thereof, two supports for two of said electrodes extending into said spaces and having a predetermined cross sectional configuration for forming a snug fit in said spaces, a support for a third of said electrodes disposed intermediate the ends of said envelope, said last named support defining a space aligned with said two aligned spaces for receiving said third of said electrodes, said two supports extending axially of said envelope to the third of said electrodes, said electrodes having cylindrical forms of different diameter and being substantially equal in length, whereby said electrodes are disposed in telescoped relation around a common axis.

6. An ultra high frequency electron discharge device having an envelope and electrodes mounted therein, said envelope defining one passageway therein, supports within said envelope for said electrodes, one of said supports extending into and forming a snug fit in said passageway, one of said electrodes being centered on said one of said supports, another of said supports defining a passageway therein aligned with said first-mentioned passageway, an electrode centered in said another of said supports, one of said electrodes being hollow, and the other of said electrodes entering said one of said electrodes, whereby said electrodes are disposed concentrically in telescoped relation.

7. An ultra high frequency electron discharge device having an envelope and electrodes mounted therein, supports within said envelope for said electrodes, end portions of said envelope and one of said supports defining aligned passageways, electrodes of equal length centered on said supports and having hollow interiors, one of said electrodes defining a space for accommodating another of said electrodes, the support for said another of said electrodes extending to locations adjacent said one of said electrodes, whereby said electrodes are disposed concentrically.

8. An ultra high frequency electron discharge device having an envelope and electrodes mounted therein, supports within said envelope for said electrodes, said supports and electrodes being aligned with respect to each other, means in said

envelope for receiving said supports in alignment with each other, said means comprising aligned interior portions of said envelope, and means for determining the longitudinal displacement of said supports for causing said electrodes to observe a registered relationship, said last named means comprising stops on said supports.

9. An ultra high frequency electron discharge device having an envelope including longitudinally joined end and intermediate sections, said sections having passageways extending longitudinally of the envelope and in alignment with each other, a disc-shaped lead-in conductor sealed across the intermediate section of said envelope and supporting an electrode at its central portion, at least two other electrodes within said envelope, supports in said end section on which said two other electrodes are centered, said supports having dimensions permitting the entry thereof in snug fits in the passageways in said end sections, and stop means on said supports for determining the longitudinal displacement of the support and the longitudinal relationship of said electrodes.

10. An ultra high frequency electron discharge device having an envelope and electrodes mounted therein, said envelope having longitudinally aligned interior portions, supports in said envelope for said electrodes, said electrodes and said supports being longitudinally aligned, said supports being received in snug engagement by said interior portions to align said supports with each other, and means for fixing the longitudinal displacement of said supports from each other, whereby said electrodes are aligned in registering relationship, at least two of said supports serving as lead-in conductors for two of said electrodes.

11. An ultra high frequency electron discharge device having an envelope and electrodes mounted therein, said envelope having longitudinally aligned interior portions, said portions defining passageways therethrough, supports within said envelope for said electrodes engaging said passageways for supporting said electrodes in mutually aligned and registering relationship, said aligned relation being determined by snug fit engagements between said passageways and said supports, stop means on said supports, said registering relation being determined by said stop means.
